Primary Examiner — John Windmuller*Assistant Examiner* — Luqman McNeil(74) *Attorney, Agent, or Firm* — Nixon & Vanderhye PC(57) **CLAIM**

The ornamental design for a “cleaning machine,” as shown and described.

DESCRIPTION

FIG. 1 is a top, front, right perspective view of a cleaning machine in accordance with my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof; and,

FIG. 7 is left side elevation view thereof.

The broken lines are included for the purpose of illustrating portions of the cleaning machine and form no part of the claimed design.

1 Claim, 5 Drawing Sheets(56)
